TWEEZERS

Walter A. Wood, Detroit, Mich.

Application April 27, 1937, Serial No. 139,259

4 Claims. (Cl. 128—354)

The present invention relates to that type of instrument known as "tweezers" and more specifically to tweezers having an automatic plucking action.

5 Among the objects of the invention is an instrument of the type indicated in which the gripping force of the jaws is maintained during the plucking movement.

Another object is a plucking device producing 10 a lateral pull of the hair or other object instead of a pull normal to the surface.

Still another object is a device of the type indicated which provides for the distinctly separate actions of gripping and plucking in one 15 continuous and rapid movement of the fingers of the operator.

Other objects and advantages will be apparent to those skilled in the art upon reference to the 20 following description and the accompanying drawing in which

Figure 1 is a perspective view of the tweezers in ordinary open position.

Figure 2 is a similar view showing the position of the parts at the end of the plucking movement.

Figure 3 is an elevational view of the tweezers showing the second position in dotted lines.

Figure 4 is a section on line 4—4 of Figure 3.

30 Figure 5 is an elevation of the gripping means. As shown, the device comprises a jaw assembly or pincette 10 (see Fig. 5), consisting of a strip of spring material having its ends 11 formed into any desired shape, but preferably bluntly pointed as shown, and bent at its middle into a loop 12 35 to bring the ends together. Suitable means such as the small eyes 13 are also formed in the strip about midway between the loop 12 and points 11.

The jaw assembly is mounted in a handle or 40 operating member 20 also consisting of spring material. This member consists of a loop of flat stock having one end 21 turned inwardly and hinged as at 22 to one of the eyes 13, the hinge being arranged to prevent swinging of the jaw assembly in the direction opposite to that indicated in Figure 3. The other end of loop 20 extends a little beyond end 21 and is formed into an eye 23 in which is enclosed one end of a wire link 24 whose other end connects with the other eye 13 on the jaw assembly.

50 In producing and assembling the device, the jaw assembly 10 is so treated that, when unrestrained, the points 11 are pressed together with sufficient pressure to grip tightly an object to be plucked or held, and the loop handle 20 is so treated that it tends to expand or open. These

two elements are so adjusted and proportioned that, when assembled, the loop handle, by virtue of its expanding bias, opens the jaws of the jaw assembly to about the position of Figures 1 and 3, against its closing bias. Further, the hinge 5 22 is so formed as to stop the element 10 parallel to the center line, while the eye 23 is slightly beyond a line extending through the two eyes 13 when the element 10 is in the full line position of Figure 3.

In the operation of the device it may be placed adjacent, for example, a hair 30, with the latter between the points 11. The initial pressure upon the arms or ends of the loop handle 20 allows the jaws 11 to close upon the hair. A further 15 pressure upon the handle 20 then causes the link 24 to rotate the member 10 about the pintle of hinge 22 to the dotted line position of Figure 3, plucking the hair laterally.

Now having described the invention, and the 20 preferred embodiment thereof, it is to be understood that said invention is to be limited, not to the specific disclosure herein set forth, but only by the scope of the claims which follow:

What I claim is:

25 1. Tweezers comprising a closable handle biased to open position, a pincette assembly mounted therein including a pair of jaws biased to closed position, the bias of the handle being arranged in opposition to that of the jaws and 30 being sufficient to maintain the latter in open position.

2. Tweezers consisting of a loop form handle of flat spring material having one of its ends turned inwardly and forming one member of a hinge structure, a jaw assembly of loop form with its jaw forming ends extending outward of the handle and having one jaw hinged to said inturned end, and a link connecting the other end of said handle to the opposite jaw, said jaw assembly being biased to closed position and said handle being biased to open position.

3. Tweezers consisting of a compressible handle assembly, a jaw member mounted for partial rotation therein, and means connecting a portion of the handle member to said jaw assembly and arranged to partially rotate the latter when said handle is compressed and return same when the pressure is relieved.

4. Tweezers consisting of a compressible handle assembly having two arms, a jaw member rotatably mounted on one of said arms, and rotating means connecting said jaw assembly and the other of said arms.
